(57) **CLAIM**

The ornamental design for a handheld medical instrument and optional docking base, as shown and described.

DESCRIPTION

FIG. 1 is a top, front perspective view of a handheld medical instrument;

FIG. 2 is a bottom, back perspective view of the instrument of FIG. 1;

FIG. 3 is a front view of the instrument of FIG. 1;

FIG. 4 is a left elevational view of the instrument of FIG. 1 (the right elevational view is a mirror image and omitted);

FIG. 5 is a back view of the instrument of FIG. 1;

FIG. 6 is a top view of the instrument of FIG. 1;

FIG. 7 is a bottom view of instrument of FIG. 1;

FIG. 8 is the same as the view of the instrument of FIG. 1 but with the instrument separated from an optional docking base (shown below the instrument in broken lines);

FIG. 9 is a bottom, back perspective view of the instrument of FIG. 8;

FIG. 10 is a front view of the instrument of FIG. 8;

FIG. 11 is a left elevational view of the instrument of FIG. 8 (the right elevational view is a mirror image and omitted);

FIG. 12 is a back view of the instrument of FIG. 8;

FIG. 13 is a top view of the instrument of FIG. 8; and,

FIG. 14 is a bottom view of the instrument of FIG. 8.

Features illustrated with broken lines form no part of the claimed design and are merely to illustrate an exemplary environment for the portion illustrated with solid lines.
